United States Patent Office

Des. 193,903
Patented Oct. 23, 1962

193,903

WATCH BRACELET COMPONENT OR SIMILAR ARTICLE

Karl C. Augenstein, Cranston, R.I., assignor to Speidel
Corporation, Providence, R.I., a corporation of Rhode
Island

Filed Mar. 20, 1962, Ser. No. 69,347

Term of patent 14 years

(Cl. D45—4)

FIG. 1

FIG. 2

FIG. 3

FIG. 1 is a top plan view of a watch bracelet component or similar article, showing my new design;

FIG. 2 is a side elevational view; and

FIG. 3 is a perspective view.

The underside of the watch bracelet component or similar article is unornamented.

The essential features of my design reside in the portions shown in full lines.

I claim:

The ornamental design for a watch bracelet component or similar article, substantially as shown and described.
